DESIGN FOR A HOT APPLICATION HEATER OR SIMILAR ARTICLE

Samuel S. Krause and Samuel E. Peskin,
Cleveland, Ohio

Application May 3, 1940, Serial No. 92,106

Term of patent 3½ years

To all whom it may concern:

Be it known that we, Samuel S. Krause and Samuel E. Peskin, citizens of the United States, residing at Cleveland, in the county of Cuyahoga and State of Ohio, have invented a new, original, and ornamental Design for a Hot Application Heater or Similar Article, of which the following is a specification, reference being had to the accompanying drawing, forming part thereof.

In the drawing,

Figure 1 is a front elevational view of a hot application heater or similar article embodying our new design;

Figure 2 is a side elevational view thereof, and,
Figure 3 is a top plan view thereof.

We claim:

The ornamental design for a hot application heater or similar article, substantially as shown.

SAMUEL S. KRAUSE.
SAMUEL E. PESKIN.
